[57] CLAIM

The ornamental design for a clamp for securing utility lines, as shown and described.

DESCRIPTION

FIG. 1 is a front, top, and right end perspective view of a clamp for securing utility lines showing my new design, in its position of use;

FIG. 2 is an enlarged left end elevational view thereof; FIG. 3 is an enlarged right end elevational view thereof; FIG. 4 is an enlarged top plan view thereof, the bottom being unornamented;

FIG. 5 is an enlarged rear elevational view thereof; and, FIG. 6 is an enlarged front, top, and right side perspective view thereof, in its opened position.

The broken line representations in FIG. 1 are for illustrative purposes only.

FIG.1**FIG.2****FIG.3**

FIG.4**FIG.5****FIG.6**
